FLOOR RACK FOR REFRIGERATOR CARS

Vinton E. Sisson, Winnetka, Ill., assignor, by
mesne assignments, to Standard Railway
Equipment Manufacturing Company, a corpora-
tion of Delaware

Application October 7, 1937, Serial No. 167,771

7 Claims. (Cl. 105—375)

The invention relates to insulated railway refrigeration cars used to transport perishable commodities, such as vegetables, fruits, berries, meats, eggs, frozen fish, etc., and to maintain such commodities while in transit within a predetermined range of temperature, thus necessitating the use of a cooling means in the summer and a heating means in the winter. It has been found that perishable commodities which have not been allowed to get too cold (freeze) or too hot (bake) have a high market value because they have a longer storage life.

In a refrigerator car water ice is associated with certain elements of the car to establish a convection circulation of air between the refrigerant chamber and the lading compartment to cool the lading in the car (as hereinafter described). A foraminous floor supports the lading in spaced relation to the insulated floor of the car.

It is desirable to allow at least some of the melted ice to remain on the insulated floor of the car below the foraminous floor to produce further insulation between the outside of the car and the air flues below the foraminous floor and also to further cool the circulating air. The melted ice (water) has a temperature of about 32° Fahrenheit when no salt is used and as low as 14° Fahrenheit when 25% salt is mixed with the lump ice, therefore, it can effectively perform the two above mentioned functions. The service movements of the car, that is, the stopping and starting, as well as the swaying movement, cause the melted ice to be thrown against the foraminous floor supports, bulkhead supports, threshold and other projections and splash through the openings in the foraminous floor and against the lading. In package lading the containers would be soiled and in loose lading such dampness might cause the commodity to rot.

An object of the invention is to position the refrigerant ice so that the melted ice (water) will drain upon the insulated floor below the foraminous floor and to construct the foraminous floor so that the melted ice (water) will not splash through the foraminous floor.

Another object is to provide a foraminous floor comprising two series of parallel slats in spaced apart planes which are positioned relative to each other and formed to prevent lateral movement of the car from splashing the melted ice through the foraminous floor. A further object is to provide stringers for supporting the slats and to provide means at the intersections of the slats and stringers to prevent the longitudinal movements

of the car from splashing the melted ice against the stringers and through the foraminous floor.

Another object is to provide means between the slats in an upper plane and the slats in a lower plane to cause them to cooperate as compression and tension members respectively of beams, thus not only providing an anti-splash foraminous floor, but also providing a very strong foraminous floor to support the lading in transit and also the more concentrated load of a loaded truck or wheeled platform carrying the lading into or out of the car.

In the drawings:

Figs. 1 and 2 show the relation of my improved floor rack to the other elements of a refrigerator car to guide the circulating air from the refrigerant chamber to the lading compartment for cooling a lading as hereinafter described.

Figs. 3, 4, 5 and 6 show modifications of one form of my invention hereinafter described, wherein means are associated with the stringers to cover the spaces between adjacent slats adjacent the stringers to prevent splashing of melted ice through the foraminous floor.

Figs. 7-10 inclusive show a modification wherein the foraminous floor comprises two groups of spaced apart slats in parallel planes and in overlapping relation with channel members adjacent the stringers to prevent melted ice from splashing through the foraminous floor.

Figs. 11-15 inclusive show a modification of the construction shown in Figs. 7-10 inclusive.

In the form of my invention illustrated the refrigerator car is provided with a bulkhead 2 separating the refrigerant chamber 3 from the lading compartment 4. The bulkhead 2 is provided with an aperture 5 adjacent the floor 6 of the car and an aperture 7 adjacent the ceiling 8 of the car with a solid wall 9 therebetween.

A refrigerant is supported by the ice supporting means 12 in the refrigerant chamber 3 in spaced relation to the floor 6 of the car and the basket (or netting) 13 spaces the refrigerant from the end wall 14 and bulkhead 2 to provide the flues 16-17. The apertured floor rack or foraminous floor supports the lading so as to provide the space 20 which communicates with the flues 16-17. A refrigerant, such as ice in the refrigerant chamber, induces a convection circulation of air from the flues 16-17, through the flue space 20 and the apertures 21 in the floor rack, and as the air is warmed by the lading, it rises and passes through the bulkhead upper opening 7 and thence through the flues 16-17, 55

and being cooled by the refrigerant, repeats the convection cycle.

When a stove or other heater is placed in the refrigerant chamber a convection circulation of air is induced in the opposite direction because the air warmed by the heater rises and falls when cooled by the lading.

In the form of my invention shown in Figs. 3 to 6 inclusive the foraminous floor 18 comprises a plurality of spaced apart slats 25 supported by stringers 26 upon the insulated floor 6 of the car, which stringers are preferably positioned parallel to the direction of movement of the circulating air and the spaced apart slats 25 extend normally to the stringers 26. The refrigerating circulating air passes through the spaces 27 between the slats. Screws, bolts, nails or any other securing means may be used.

In the modification shown in Fig. 3 the channel shape member 30 is positioned between each stringer 26 and the slats 25 with the web 31 thereof resting upon the stringer 26 and the depending flanges 32 spaced from the stringer so that the water being splashed against the stringer 25 will be caught by the depending flanges and not allowed to pass through the spaces 27 between the slats.

In the modification shown in Fig. 4 the members 36 are secured to each side of the stringer 26 which cover the spaces 27 between adjacent slats 25 to stop the splashing water.

In the modification shown in Fig. 5 short members 40 are secured to the stringer 26 in the spaces 27 between adjacent slats 25 which extend beyond both sides of the stringer to stop the splashing water. The upper surfaces 41 of these members are preferably sloped to provide a watershed.

In the modification shown in Fig. 6 the stringer 45 is preferably made of two metallic strips of metal secured together at 46 (preferably by welding) and formed to provide horizontally disposed portions 47 supporting the slats 25 and a substantially vertical portion 48 supporting the horizontal portions 47 upon the insulated floor 6 with the horizontal portions 47 having depending flanges 49 to stop splashing water. The arms of the vertical portion preferably diverge for stability.

In the modifications of my invention shown in Figs. 7-15 inclusive the foraminous floor 18 comprises a plurality of spaced apart slats 60 in one plane in spaced relation to a plurality of spaced apart slats 61 in a substantially parallel plane with the slats in each plane being opposite the spaces 62-63 between the slats in the other plane and preferably in overlapping relation therewith so that the service movements of the car will not cause the melted ice to splash through the spaces 62 between the slats. These slats may be made of wood or formed from metallic sheets or some may be wood and others metal. Any convenient stringer may be used to support the slats in both of said planes, which stringers preferably extend normally to the slats.

In the modifications shown in Figs. 7-10 inclusive the stringers 65 are provided with upper surfaces 66 supporting the medial portion of the upper slats 60 and lower surfaces 67 supporting the lower slats 61 so that a single stringer supports the slats in both the upper and lower planes. In this modification the upper slats 60 are made of wood and the lower slats 61 are made of metallic sheet provided with depending stiffening flanges 68, which flanges 68 also act as baffles to stop

splashing water. Grooves 69 are provided for the flanges 68. I also provide anti-splash pieces 70 extending parallel to the slats 60-61 (and preferably between the slats in different planes) at the intersections of the slats with the stringers 65. These anti-splash pieces extend a relatively short distance on each side of the stringer 65 so as to prevent water from splashing against the stringer and re-splashing through the spaces 62 between the slats. These anti-splash pieces preferably support the margins 71 of the upper slats upon the stringers. In this modification I have also shown a channel shape member 73 lying over the top of the stringer, as shown more fully in Fig. 7. Fig. 8 is a section through the lower slat 61, while Fig. 9 is a section through the upper slat 60.

In the modification shown in Figs. 11-14 inclusive the anti-splash pieces, instead of being made of a wooden strip, as shown in Fig. 10, comprises a U-shape member 80 resting in the notch 81 in the stringer 82 and extending beyond both sides of the stringer (at 83), which U-shape member is provided with flanges 84 projecting lengthwise of the stringer 82 to provide baffles for splashing water. Fig. 11 shows the notched stringer. Fig. 12 shows the anti-splash member 80 in place. Fig. 13 shows the lower slat 84 also in position, and Fig. 14 shows the construction of the upper (85) and lower (84) slats also in position. The anti-splash member 80 prevents the service movements of the car from causing the melted ice to splash through the spaces between the slats.

The modification shown in Fig. 15 shows the slats 90-91 made of metallic sheets, with the slats 90 in the upper plane formed with stiffening depending marginal flanges 92 and with the slats 91 in the lower plane provided with upstanding marginal flanges 93; that is, each series of slats is provided with flanges projecting toward the slats in the other series so that flanges cooperate to provide a baffling structure against the splashing water. An anti-splash piece 95 is shown. All slats are supported by the stringer 96.

The accompanying drawings illustrate the preferred form of the invention, though it is to be understood that the invention is not limited to the exact details of construction shown and described, as it is obvious that various modifications thereof, within the scope of the claims, will occur to persons skilled in the art.

I claim:

1. In a refrigerator car having an insulated floor, a foraminous floor above the insulated floor, a space between said floors and ice associated with other elements of the car to induce an air current in said space upon melting thereof, said ice being positioned so that the melted ice will drain upon said insulated floor, said foraminous floor comprising a plurality of spaced apart slats in one plane in spaced relation to a plurality of spaced apart slats in a substantially parallel plane with the slats in each plane being opposite the spaces between the slats in the other plane and in overlapping relation therewith whereby the service movements of the car will not cause the melted ice to splash through the spaces between the slats.

2. In a refrigerator car having an insulated floor, a foraminous floor above the insulated floor, a space between said floors and ice associated with other elements of the car to induce an air current in said space upon melting thereof, said ice being positioned so that the melted ice will

- drain upon said insulated floor, said foraminous floor comprising a plurality of spaced apart slats in one plane in spaced relation to a plurality of spaced apart slats in a substantially parallel plane 5 with the slats in each plane being opposite the spaces between the slats in the other plane and in overlapping relation therewith, the slats in one of said planes each formed with stiffening marginal flanges projecting toward the slats in the other of said planes and positioned to form baffles whereby the service movements of the car will not cause the melted ice to splash through the spaces between the slats.
3. In a refrigerator car having an insulated floor, a foraminous floor above the insulated floor, a space between said floors and ice associated with other elements of the car to induce an air current in said space upon melting thereof, said ice being positioned so that the melted ice will 10 drain upon said insulated floor, said foraminous floor comprising a plurality of spaced apart slats in one plane in spaced relation to a plurality of spaced apart slats in a substantially parallel plane with the slats in each plane being opposite the spaces between the slats in the other plane, a 15 stringer extending normally to and supporting said slats, and means to prevent said melted ice from splashing against said stringer and passing through the foraminous floor between the slats.
6. In a refrigerator car having an insulated floor, a foraminous floor above the insulated floor, a space between said floors and ice associated with other elements of the car to induce an air current in said space upon melting thereof, said ice being positioned so that the melted ice will 20 drain upon said insulated floor, said foraminous floor comprising a plurality of spaced apart slats in one plane in spaced relation to a plurality of spaced apart slats in a substantially parallel plane with the slats in each plane being opposite the spaces between the slats in the other plane, a 25 stringer extending normally to and supporting the slats in both of said planes and anti-splash pieces between adjacent slats in different planes at the intersections of said slats with said stringer 30 to prevent said melted ice from splashing against said stringer and passing through the foraminous floor between the slats.
7. In a refrigerator car having an insulated floor, a foraminous floor above the insulated floor, a space between said floors and ice associated with other elements of the car to induce an air current in said space upon melting thereof, said ice being positioned so that the melted ice will 35 drain upon said insulated floor, said foraminous floor comprising a plurality of spaced apart slats in one plane in spaced relation to a plurality of spaced apart slats in a substantially parallel plane with the slats in each plane being opposite the spaces between the slats in the other plane, a 40 stringer extending normally to and supporting the slats in both of said planes, and an inverted channel shaped member having the web thereof between the stringer and the slats in the upper plane and the depending flanges thereof spaced 45 away from the stringer whereby said member prevents the melted ice from splashing against the stringer and resplashing through the spaces between the slats in the upper plane.
5. In a refrigerator car having an insulated floor, a foraminous floor above the insulated floor,

VINTON E. SISSON. 55
